(57) **CLAIM**

The ornamental design for a surface vise, as shown and described.

DESCRIPTION

FIG. 1 is a perspective view of a surface vise of this invention in an extended position, depicted with a portion (shown in broken lines) of a typical woodworking bench having round dog holes on which the surface vise may be used.

FIG. 2 is a top plan view of the surface vise shown in FIG. 1, with the pivoting handle in a tilted position;

FIG. 3 is a right side elevation view thereof;

FIG. 4 is a working end elevation view thereof;

FIG. 5 is a handle end elevation view thereof;

FIG. 6 is a bottom plan view thereof; and,

FIG. 7 is a left side elevation view thereof.

The features shown in broken lines in the drawings depict environmental subject matter only and form no part of the claimed design.
